(57) **CLAIM**

The ornamental design for a heat sink clip and attachment, as shown and described.

DESCRIPTION

FIG. 1 is a front perspective view of a heat sink clip and attachment showing our new design;

FIG. 2 is a bottom perspective view of the heat sink clip and attachment showing the new design;

FIG. 3 is a front view of the heat sink clip and attachment shown in FIG. 1;

FIG. 4 is a back view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 2;

FIG. 9 is an exploded parts view thereof showing the heat sink clip and attachment, the mounting shown in broken lines;

FIG. 10 is an assembled parts view thereof showing the heat sink clip and attachment, the mounting shown in broken lines.

FIG. 11 is a cross-sectional view along the line 11 of FIG. 7; and,

FIG. 12 is a partial and enlarged cross-sectional view of the detail 12 observed in dot-dash line(s) 12 of FIG. 11.

The broken lines illustrate the environmental mounting and form no part of the claimed design.
